Primary Examiner — Jennifer L Rempfer

Assistant Examiner — Michelle Marquart Christeon

(57) **CLAIM**

The ornamental design for a table for computer terminals as shown and described.

DESCRIPTION

- 1.1 : Perspective
- 1.2 : Front
- 1.3 : Back
- 1.4 : Right
- 1.5 : Left
- 1.6 : Top
- 1.7 : Bottom
- 2.1 : Perspective
- 2.2 : Front
- 2.3 : Back
- 2.4 : Right
- 2.5 : Left
- 2.6 : Top
- 2.7 : Bottom

The broken lines showing portions of the table for computer terminals form no part of the claimed design.

(Continued)

The characteristic features of the design lie in the combination of the shape and pattern.

1 Claim, 14 Drawing Sheets
